DESIGN FOR A STOCKING

Ernest Albin Nebel, Paterson, N. J.

Application March 9, 1937, Serial No. 68,083

Term of patent 7 years

To all whom it may concern:

Be it known that I, Ernest Albin Nebel, a citizen of the United States, residing at Paterson, in the county of Passaic and State of New Jersey, have invented a new, original, and ornamental Design for Stockings, of which the following is a specification, reference being had to the accompanying drawing, forming part thereof, and in which:

Figure 1 is a side view of the complete stocking embodying the present design, which is shown only fragmentarily in the leg and foot portions, and

I claim:

The ornamental design for a stocking as shown and described.

ERNEST ALBIN NEBEL.
